APPARATUS FOR AND METHOD OF EXCITING ELECTRIC OSCILLATIONS.

1,189,791.

Specification of Letters Patent.

Patented July 4, 1916.

Application filed November 4, 1911. Serial No. 658,539.

To all whom it may concern:

Be it known that I, EMORY LEON CHAFFEE, a citizen of the United States, and resident of Somerville, in the county of 5 Middlesex and State of Massachusetts, have invented new and useful Improvements in Apparatus for and Methods of Exciting Electric Oscillations, of which the following is a specification.

10 The invention relates to radio telegraphy and telephony, and more particularly to an apparatus for and a method of producing high frequency electrical oscillations.

The apparatus and method are discussed 15 in detail in my paper entitled, "A new method of impact excitation of undamped oscillations and their analysis by means of Braun tube oscillographs," published in the *Proceedings of the American Academy of Arts and Sciences*, Vol. XLVII No. 9, November, 1911, page 267.

The object of my invention, which practical demonstration proves to have been attained, is to provide in a high degree of perfection uniform and regular electric oscillations of small damping and large train frequency, and, moreover, to provide such oscillations by means of a simple, economical and continuously reliable apparatus, 30 which operates with freedom from inherent vibrations of audible frequency, and is therefore applicable to any uses where such oscillations are required; particularly to radio-telephony. The fact that by the ap-

35 paratus and method, presently herein to be particularly described, there have been obtained continuous, practically undamped oscillations of several amperes at twenty meters wave length, corresponding to a frequency of 1.5×10^7 oscillations per second, sufficiently suggests the utilities to which my invention may be applied.

In the drawings hereto annexed, which illustrate my invention, Figure 1 is a longitudinal elevation, partly in section, of a discharge-gap; Fig. 2 is half end elevation, half cross section at the line 2, 2 of Fig. 1; Fig. 3 is a diagram, showing a mode of connecting the discharge-gap in a radio-telephonic system; Fig. 4 is a diagram showing 50 an alternative method of connection, for ob-

taining an increased power-output; Fig. 5 is a diagram showing another alternative method of connection, for the same purpose; Figs. 6 and 7 are diagrams illustrating the action of the discharge-gap, and the relation between exciting impulses and excited oscillations.

The apparatus.—The discharge-gap, indicated comprehensively in Fig. 3 by the letter G, is shown in detail in Figs. 1 and 2. The electrodes or terminals, e, e', are metallic plugs tapered to fit tightly in the bores of relatively massive metallic supports t, t'. These supports are preferably ribbed as at 65 D, D', and blackened, so as freely to radiate heat. The supports t, t' are threaded into tapped holes in the metal plates c, c' which are separated and insulated by a centrally perforated slab b, of hard rubber, asbestos 70 board, or other adequate insulating material. Insulating knobs r, r' are provided for adjustment of the supports t, t', and consequently the electrodes or terminals e, e'. Binding posts P, P' serve for connecting the discharge-gap in the electrical system, and pipes i and o provide inlet and outlet respectively for hydrogen or hydrocarbon gas, to maintain an atmosphere productive of an advantageous volt-ampere 75 characteristic, surrounding the discharge. This atmosphere of hydrogen or hydrocarbon, if moist, as is preferable, also probably has a chemical action upon the electrodes. 85

The electrodes e, e' are composed of dissimilar metals, of such a character and so disposed that when the apparatus is active, a much larger discharge current passes across the gap in one direction than in the 90 opposite. The best discharge-gap construction known to me at present is one in which the cathode is a highly oxidizable metal, for example, aluminum and the anode copper or silver,—anode and cathode 95 being determined with reference to a unidirectional source of current in the circuit which includes the discharge-gap; the separation between the two electrode faces being quite small, say about .07 mm. The area of 100 each electrode face may conveniently be about two square cm., and the two faces

should be accurately parallel and smooth. While the above specifications express the preferred condition, an alloy of aluminum, or magnesium, or an alloy of magnesium, or 5 an alloy composed of aluminum and magnesium, or a mixture of alloys of the two metals, will produce effects the same in kind as those obtained with the preferred aluminum electrode. While copper or silver is 10 preferable for the anode-material, the metal of which the anode may be composed may be very widely varied without seriously interfering with the correct and efficient operation of the discharge-gap.

15 The rectification-effect in such a discharge-gap as above described is believed to be due, first: to the practically instantaneous reestablishment of the high initial gap-resistance when the current becomes zero, 20 probably because of the formation of a film of insulating material, probably an oxid on the aluminum or equivalent terminal; second: to the higher cathode-drop of the anode-metal, and third: to the absorption 25 of energy by the secondary. The existence of the insulating film is plainly evident upon an aluminum terminal which has been in use for a short time in the gap, and is seen upon a removed terminal as a very 30 hard black coating which tests show to be practically non-conductive of electricity. This film probably assists the rectification by its alternate reduction by the hydrogen and subsequent oxidation by the oxygen introduced with the original aluminum or 35 which is introduced by moisture carried in with the hydrogen.

Figs. 3, 4 and 5 illustrate modes in which the above described discharge-gap may be 40 associated with the components of an oscillating system. Referring especially to Fig. 3: T represents an oscillation-transformer, shown as inductively coupled. D C represents a direct current source—of say 400 to 45 500 volts more or less—connected with the discharge-gap G through a supply circuit including the series resistance R and series inductances L L. C represents a condenser, connected across the circuit, P is the 50 primary coil and S the secondary of the oscillation transformer T. The condenser C and primary coil P form with the discharge-gap G, an exciting circuit which is 55 metallically closed except for the space of the gap, and the dielectric of the condenser. The secondary coil S is connected to the antenna A, and to ground; a telephone transmitter M—say, of the microphonic type—is inserted as shown in the oscillation or radiating circuit which comprises 60 the secondary coil S. Other modes of inserting the telephone are well known, and may be employed alternatively, so long as the telephone is in such position as to vary

the current flowing in the antenna by the 65 imposition of periodic undulation having the characteristic of articulate speech.

Figs. 4 and 5 need not be described at length. They indicate arrangements of discharge-gaps either in series or in parallel 70 for the purpose of obtaining a greater power-output.

Adjustment of the apparatus, and the method of operation.—The circuits represented by Fig. 3 (likewise Figs. 4 and 5) 75 may be adjusted to a relation which insures efficient operation, by variation of one or more of the quantities represented by R, P, C or S. This adjustment is, however, not such as to produce equivalent or approxi- 80 mately equivalent time-periods of the primary and secondary oscillation circuits, but is a novel adjustment, functionally significant in the effective operation of this invention, and an important characteristic 85 of the new method herein described. This novel adjustment may be explained by reference to Figs. 6 and 7.

Figs. 6 and 7 are diagrams in which the ordinates represent current and are plotted 90 against abscissæ representing time. The heavily drawn curve I' represents the current in the primary or exciting circuit (C, P, G, Fig. 3,) and the lightly drawn curve I², the current in the secondary or 95 oscillation circuit, (A, S, M, Fig. 3). Both of these curve representations are approxi- 100 mate. The current I' in the primary circuit consists of recurrent rectified impulses, in each of which current builds up to a maximum and subsides to zero, but does not reverse to an opposite maximum. Tracing the recurrences from their beginning: The potential of the condenser C reaches a value 105 sufficient to overcome the discharge-gap resistance; then, on being overcome, the gap-resistance falls to a very low value; and thereupon the discharge of the condenser together with the main current which previously charged the condenser, rushes across 110 the gap and through the primary coil P. At the end of this current-rush the current through the gap is zero, and the condenser has an inverse charge; the main current from the source D C thereupon neutralizes 115 the inverse charge of the condenser and re-charges it in the initial direction, increasing the condenser potential until the gap-resistance again breaks down. During the interval between successive primary dis- 120 charges the secondary, excited by the primary, continues to oscillate in its own free period, with such damping as is in- 125 evitably due to the conditions of the secondary circuit (regarded solely) such as resistance and radiation. Although, for this reason, the secondary oscillation cannot strictly be characterized as absolutely un-

damped, it can be maintained in substantial constancy by causing the primary exciting impulse to recur at time intervals which are integral multiples of the time-period of the 5 secondary oscillation, and in such phase relation with the secondary oscillation that each primary excitation comes in to maintain and amplify the declining secondary oscillation. By so renewing the excitant 10 effect, the secondary oscillation becomes practically continuous, uniform, and undamped. By virtue of the inductances L, L , in the source-circuit, the condenser C (Fig. 3) can attain higher potentials than 15 the source itself; the maximum condenser potential is determined by the breaking down potential of the discharge-gap G . This may be assumed to be constant, or practically so; thus the number of 20 discharges per second depends upon the supply current and the condenser.

On account of the definite, though distorted, form of the primary impulse, and the resulting impulse of electromotive force 25 generated in the secondary, for the most efficient operation of the system the primary-current rush should have a definite relation as to period of recurrence and phase with respect to the secondary oscillations. 30 This requirement is answered by two conditions of tuning or timing the recurrence-period of the primary to the oscillation period of the secondary; to wit;

First. An adjustment of the constants of 35 the primary circuit so that its natural time-period (when the discharge-gap is short-circuited, or replaced by a non-rectifying gap) is about 1.7 times the natural period of the oscillations of the secondary. Fig. 6 40 approximately shows the resulting time-relation between the recurrent rectified primary impulses and the secondary oscillations. This figure shows the fact that the primary discharge (I') lasts for a time 45 about equal to one complete double swing of the secondary current (shown by sine curve), and that the wave-form of the primary discharge current plotted against time is such that its time derivative is nearly of 50 the same period as the secondary current. It is to be observed that this is not to say that the primary current is equiperiodic with the secondary current, and the whole 55 matter will be best understood by consideration of the following statement of facts. The primary current is in the form of impulses practically unidirectional. When the primary current is increasing, it impresses 60 an electromotive force on the secondary in one direction, and when the primary current is decreasing it impresses the electromotive force, on the secondary, in the opposite direction. This is an effect determined by the time derivative of the pri-

mary current. Therefore while the time required for the current of the discharge impulse starting at zero to again become zero is greater than one-half the complete period (double swing) of an oscillation in the oscillation circuit (being slightly less than the 65 time of one complete double swing), nevertheless the electromotive force impressed thereby on the oscillation circuit has a frequency substantially the same as the natural frequency of the oscillation circuit. The 70 natural period of the current oscillation of the primary circuit as determined by its inductance and capacity, or as determined by measurements, if the gap hereof were short-circuited or replaced by an ordinary 75 gap, is about 1.7 times the natural period of the secondary. This form of adjustment is an important feature of novelty herein, being characterized by the necessity of making the primary of a period considerably 80 different from that of the secondary, and giving the primary current a characteristic form which excites oscillations in the secondary circuit. There is a distinct advantage in having the primary and secondary 85 circuits non-equiperiodic, in that thereby the primary current wave may be made to have a derivative with respect to time in such form as to excite oscillations in the secondary; while the time derivative of the 90 secondary current is of such form as not to be of proper period to excite oscillations in the primary and therefore obviates return of energy to the primary circuit. The effect of the secondary current in its reaction on 95 the primary is very different from its effect if the two circuits were equiperiodic. In the latter case the oscillatory secondary current would give an oscillatory electromotive force in primary and if the primary were 100 periodic and of the same period as the secondary, the primary would be excited by the secondary and would take energy away from the secondary. By having the primary detuned or of different period from 105 that of the secondary, as herein described, the primary is rendered immune from excessive secondary reactions and consequent waste of energy in the primary. The secondary reaction on the primary is so small 110 as to have effect only when the primary condenser is recharged from the source and is just ready to redischARGE, and then the slight reaction of the secondary is sufficient 115 to precipitate the primary discharge in 120 proper phase to add energy to the secondary circuit.

Second. An adjustment of the supply current and primary condenser so that the frequency of primary impulses is a submultiple (1/2 to 1/n) of the secondary oscillation frequency. (Figs. 6, 7.) The second adjustment mentioned is not important

when a large number of secondary oscillations intervene between successive primary impulses, that is: when n in the fraction $1/n$ is large; but is important when n equals 5 2 or 3, or, a small number of secondary oscillations intervene between primary impulses.

Under such conditions of timing, the phase-relation between the primary impulses and secondary oscillations adjusts 10 itself automatically. Across the discharge-gap in the primary (between impulses) there is impressed the condenser-potential, and superposed on this, the potential-ripples induced by the oscillating secondary. As the condenser-potential approaches the 15 breaking down point of the discharge-gap, one of these ripples will supply just enough increment to serve as a trigger, precipitating the discharge at the precise instant in relation to the secondary phase which is suited to the effective reception in the secondary of the excitation from the primary impulse, which comes in to boost the secondary oscillation, and is extinguished before arriving at a phase relation which would retard the secondary oscillation. It is thus clear, that if the primary discharge frequency is very low, referred to the secondary oscillation frequency, the potential impressed by the condenser cannot rise fast enough to break down the gap at a minimum of potential-ripple induced by the secondary, but must discharge on a ripple-maximum, whereas if the primary discharge frequency is high, say: 1/2 or 1/3 the secondary oscillation frequency, the rise of potential impressed by the condenser must be correspondingly steep; so steep in fact, that a discharge might occur at a minimum of induced potential ripple if the discharge frequency were not timed as above described.

What I claim and desire to secure by Letters Patent is:—

1. Means for producing electrical oscillations, which comprises an exciting circuit containing a charging condenser, and containing also a discharge-gap constructed and 50 operated to rectify the condenser-discharges; and a radiating circuit receiving the resulting rectified current-pulses and having oscillations of its own natural period set up in it thereby; the constants of the exciting circuit being such that its natural time-period, exclusive of the resistance differential of the discharges, is about one and seven tenths times that of the radiating circuit.

2. Means for producing electrical oscillations, which comprises a source of current-supply, an exciting circuit containing a charging condenser and containing also a discharge-gap which is constructed and operates to rectify the condenser-discharges,

and a radiating circuit receiving the resulting rectified current-pulses and having oscillations of its own natural period set up in it thereby; the conditions of the supply-current and of the condenser being such that the frequency of primary impulses is a submultiple of the natural period of the radiating circuit. 70

3. Means for producing electrical oscillations, which comprises an exciting circuit containing a charging condenser, and containing also a discharge-gap constructed and operating to rectify the condenser-discharges; and a radiating circuit receiving the resulting rectified current-pulses and having oscillations of its own natural period set up in it thereby; the constants of the exciting circuit being such that its natural period, exclusive of the resistance differential of the discharges, is about one and seven tenths times that of the radiating circuit; and the conditions of the supply-current and of the condenser being such that the frequency of primary impulses is a submultiple of the natural period of the radiating circuit. 80

4. Means for producing single-period oscillations in an electric wave radiator, which comprises a source of supply-current, and an exciting circuit coupled to such radiator and including a rectifying discharge gap, the gap-structure being provided with means for removing discharge-heat from the gap-terminals; the supply-current and exciting circuit being conditioned to permit radiator-oscillations to precipitate successive gap-discharges of lower frequency than the radiator-oscillations but in phase to boost the latter, and to extinguish said gap discharges before occurrence of a phase-relation retarding radiator-oscillations. 95

5. An apparatus for producing sustained electrical oscillations having, in combination, an oscillation circuit in which the sustained oscillations are maintained, an exciting circuit coupled with the oscillation circuit, a condenser in the exciting circuit, a supply circuit for charging the condenser, and a discharge gap in the exciting circuit for permitting single uni-directional current discharges through the exciting circuit, said oscillation circuit reacting on the exciting circuit to cause ripples of induced electromotive force therein which serve to trigger off the discharge in proper timed relation to the oscillations in the oscillation circuit so as to maintain and amplify the declining oscillations. 110

6. An apparatus for producing sustained electrical oscillations having, in combination, an oscillation circuit in which the sustained oscillations are maintained, means for maintaining said oscillations comprising an exciting circuit, a condenser in the exciting circuit, a discharge gap in the ex- 125

citing circuit, means for charging the condenser at such a rate that the condenser does not receive a charge sufficient to break down the discharge gap until after at least one complete oscillation in the oscillation circuit has taken place since the end of the preceding discharge, said oscillation circuit reacting on the exciting circuit while the condenser is receiving its charge to cause induced ripples of electromotive force across the discharge gap to trigger off the discharge in such relationship with the oscillations as to maintain and amplify the declining oscillations in the oscillation circuit.

15 7. An apparatus for producing sustained oscillations having, in combination, an oscillation circuit in which the sustained oscillations are maintained, and means for maintaining such oscillations comprising an exciting circuit coupled with the oscillation circuit and means coöperating therewith for producing in the exciting circuit current impulses the duration of which is greater than one-half the complete period of the oscillations in the oscillation circuit and which occur at time intervals which are integral multiples of the time period of the oscillations in the oscillation circuit and which impress on the oscillation circuit an electromotive force of a frequency substantially the same as the natural frequency of the oscillation circuit.

8. An apparatus for producing electrical oscillations having, in combination, an oscillation circuit containing inductance and capacity, an exciting circuit coupled with the oscillation circuit and containing inductance, a condenser and a discharge gap, a supply circuit for charging the condenser at such a rate that the condenser does not receive a charge sufficient to break down the discharge gap until after at least one complete oscillation in the oscillation circuit has taken place since the end of the preceding condenser discharge, the capacity and inductance in the exciting circuit being proportioned to cause a discharge wave in the exciting circuit of greater wave length than the oscillations in the oscillation circuit, said discharge gap, in conjunction with the absorption of energy from the exciting circuit by the oscillation circuit during the condenser discharge, being constructed and arranged to extinguish the condenser discharge after a single uni-directional discharge wave has taken place.

9. An apparatus for producing electrical oscillations having, in combination, an oscillation circuit containing inductance and capacity, an exciting circuit containing inductance and a condenser and a discharge gap, coupled with the oscillation circuit and having a natural time period greater than that of the oscillation circuit, a supply circuit for charging the condenser and co-

operating with the exciting circuit to produce therein current discharge waves of a duration greater than one-half that of the complete period of the oscillations in the oscillation circuit but of such form as to impress on the oscillation circuit an electromotive force of a frequency substantially the same as the natural frequency of the oscillation circuit and thereby excite oscillations in the oscillation circuit of the natural oscillation period of said circuit.

10. An apparatus for producing electrical oscillations having, in combination, an oscillation circuit containing inductance and capacity, an exciting circuit containing inductance and a condenser and a discharge gap, coupled with the oscillation circuit and having a natural time period of oscillation of about 1.7 that of the oscillation circuit and operating in conjunction with the oscillation circuit to cause the condenser discharges to take the form of current waves of greater duration than one-half the complete oscillations in the oscillation circuit, a current source connected through inductance to the exciting circuit for charging the condenser at such a rate that at least one complete oscillation occurs in the oscillation circuit between the end of one condenser discharge and the beginning of the following condenser discharge.

11. An apparatus for producing electrical oscillations having, in combination, an oscillation circuit in which the oscillations are induced, and means for exciting such oscillations comprising an exciting circuit containing a condenser and coupled with the oscillation circuit and means coöperating therewith for producing in the exciting condenser discharges for which the time required for the current starting at zero to again become zero is greater than one-half the complete period of the oscillations in the oscillation circuit and of such a wave shape as to impress on the oscillation circuit an electro-motive force of substantially the same period as the oscillations.

12. An apparatus for producing sustained electrical oscillations having, in combination, an exciting current including inductance and capacity and a discharge gap, an oscillating circuit coupled with the exciting circuit and containing inductance and capacity, a supply circuit for charging the condenser in the exciting circuit, said supply circuit serving to charge the condenser so that it discharges across the discharge gap before the oscillations in the oscillation circuit die down, the oscillations in the oscillation circuit serving to impress ripples of electromotive force upon the exciting circuit to trigger off the condenser discharge in a predetermined phase relation to the said oscillations, the inductance and capacity in the exciting circuit being proportioned so

as to produce a discharge wave in the exciting circuit of greater duration than one-half the complete period of the oscillations but which is extinguished before arriving at 5 a phase relation which retards the oscillations.

13. An apparatus for producing electrical oscillations having, in combination, an oscillation circuit in which the oscillations are induced, and an exciting circuit coupled with the oscillation circuit and means co-operating therewith for producing in the exciting circuit current impulses for which the time required for the current starting at 10 zero to again become zero is greater than one-half the complete period of the oscillations in the oscillation circuit and of such a wave shape as to impress on the oscillation circuit an electro-motive force of substantially the same period as the oscillations.

14. An apparatus for producing electrical oscillations comprising an oscillation circuit, and an exciting circuit and means co-operating therewith for causing in the exciting circuit current impulses of a duration about equal to one complete oscillation in the oscillation circuit but having a wave form such as to impress on the oscillation circuit an electromotive force of about the same period as the oscillations to be produced.

15. An apparatus for producing electrical oscillations having, in combination, an oscillation circuit, an exciting circuit coupled with and out of tune with the oscillation circuit, and means for causing in the exciting circuit current impulses of a form such as to impress on the oscillation circuit an electro-motive force of substantially the natural oscillation period of said oscillation circuit, 35 the detuning of the circuits serving to effectively hinder a re-transfer of energy from the oscillation circuit to the exciting circuit.

16. An apparatus for producing electrical oscillations comprising an oscillation circuit, an exciting circuit coupled therewith but having a considerably different natural time period, and means co-operating therewith for causing in the exciting circuit current impulses of such a wave form as to impress on the oscillation circuit an electro-motive force having substantially the natural period of the oscillation circuit.

17. An apparatus for producing sustained electrical oscillations comprising an oscillation circuit, an exciting circuit coupled therewith, and means co-operating therewith for causing current impulses in the exciting circuit, the oscillation circuit reacting on the exciting circuit to trigger off the current impulses in proper phase relation to maintain and amplify the declining oscillations.

18. An apparatus for producing electrical oscillations comprising an oscillation circuit and an exciting circuit coupled therewith, 60 and means for causing in the exciting circuit

current impulses of such a wave form as to induce oscillations in the oscillation circuit of substantially the natural period of said circuit, the oscillation circuit reacting on the exciting circuit to cause the frequency of the 70 impulses to be a sub-multiple of the frequency of the oscillations.

19. An apparatus for producing electrical oscillations having, in combination, an oscillation circuit containing inductance and capacity, an exciting circuit coupled with the oscillation circuit and containing inductance, a condenser and a discharge gap, a supply circuit for charging the condenser at such a rate that the condenser does not receive a 80 charge sufficient to break down the discharge gap until after at least one complete oscillation in the oscillation circuit has taken place since the end of the preceding condenser discharge, the capacity and inductance in 85 the exciting circuit being proportioned to cause a discharge impulse in the exciting circuit of a greater duration than one half the complete period of the oscillations in the oscillation circuit, said discharge gap in 90 conjunction with the absorption of energy from the exciting circuit by the oscillation circuit during the condenser discharge, being constructed and arranged to quickly extinguish the condenser discharge.

20. The method of producing electrical oscillations in an oscillation circuit which consists in setting up in an exciting circuit coupled with the oscillation circuit discontinuous current impulses, and causing the oscillations in the oscillation circuit to react on the exciting circuit to trigger off the current impulses in proper timed relation to the oscillations in the oscillation circuit to maintain and amplify the declining oscillations.

21. The method of producing electrical oscillations which consists in inducing a series of oscillation-exciting electro-motive forces by means of discontinuous unidirectional current impulses having a duration greater than one-half the complete period of the oscillations sought to be produced, and applying such electro-motive forces to a circuit containing inductance and capacity 110 to set up free oscillations therein.

22. The method of producing electrical oscillations which consists in generating current impulses of a duration considerably greater than one-half the complete period 120 of the oscillations sought to be produced but of a form such as to induce an electro-motive force of substantially the same period as that of the oscillations and applying such electromotive forces to an oscillation circuit, and in extinguishing the current impulses before the induced electro-motive force arrives at a phase relation such as to materially retard the oscillations.

23. The method of producing sustained

electrical oscillations which consists in impressing exciting impulses on an oscillation circuit, and in causing the oscillations to react on the exciting impulses so as to cause
5 the impressed impulses to recur at time intervals which are integral multiples of the time period of the oscillations.
